UNITED STATES PATENT OFFICE.

JACOB H. BODINGER, OF NEW YORK, N. Y.

WATER-CLOSET BOWL.

Application filed August 11, 1921. Serial No. 491,379.

To all whom it may concern:

Be it known that I, JACOB H. BODINGER, a citizen of the United States, and a resident of New York, borough of Manhattan, in the 5 county of New York and State of New York, have made and invented certain new and useful Improvements in Water-Closet Bowls, of which the following is a specification.

My invention relates to water closet bowls 10 and has for its object to provide a bowl so constructed that should the liquid seal for any cause become broken it will be immediately and automatically reestablished.

Where a number of closet bowls are connected to a single waste pipe, as, for example, in apartment houses, it has been found that occasionally the flushing of a bowl will set up a vacuum within the waste pipe which will tend to break the liquid seal of the various closet bowls connected to the drainage pipe and located below the particular bowl which has been flushed. In order to overcome this it has heretofore been proposed to provide an additional vent pipe for each 25 bowl and connect it to the waste pipe at a point above the main connection of the bowl to the waste pipe. This, however, as will be readily appreciated, involves considerable expense. A further disadvantage to the 30 closet bowl as heretofore constructed, has been caused by the evaporating of the water of the liquid seal when the bowl is not flushed over a considerable period of time, this evaporating of the water of the liquid seal allowing for the escapement of sewer 35 gases. This escapement of the sewer gases may also occur where the gradual spilling of the water of the liquid seal is caused by varying wind pressure down the vent pipe.

It is accordingly an object of my invention to provide a water closet bowl which is simple in construction and so designed and arranged that should the liquid seal for any cause whatever become broken a quantity of 40 water will be automatically discharged into the bowl and the liquid seal accordingly reestablished.

A further object is to accomplish the aforementioned ends in a simple and practical 45 manner, and to provide a bowl which will remain in a clean and sanitary condition, and with the foregoing and other objects in view, my invention consists in the improved water closet bowl illustrated in the accompanying drawing and hereinafter described and claimed, and in such variations and

modifications thereof as will be obvious to those skilled in the art to which my invention relates.

In the accompanying drawing:

Figure 1 is a top plan view of my improved closet bowl, a portion thereof being broken away and illustrated in section;

Figure 2 is a view in vertical section taken on the line 2—2 of Figure 1; and

Figure 3 is a detail view in section taken on the line 3—3 of Figure 2.

Referring specifically to the several views, wherein similar reference numerals designate corresponding parts throughout, my 70 improved closet bowl is formed with the usual body 10, having a downwardly projecting trap wall 11 which extends below the upper rim of the usual basin portion 12, so that when the basin portion is filled with 75 water a liquid seal 13 will be maintained between the vent or soil pipe 14' and the upper open extremity of the bowl.

The flush tank 14 has the pipe 15' leading into the body of the bowl and is adapted 80 to flush the same in the usual manner. Carried by the bowl 10, and preferably formed integrally with the same, is an auxiliary compartment 15, the same communicating with the bowl below the top surface of the 85 liquid seal through the restricted opening 16 and with the bowl at a considerable distance above the top of the liquid seal, through the air vent 17. The auxiliary compartment 15 is formed with the side walls 90 18 and top wall 19, all of which are preferably formed integrally with the bowl proper, so as to present a neat and pleasing appearance, and at the same time provide for a rigid, strong and economical construction. 95

A float valve 20 is located within the auxiliary compartment 15 and has the float 21 carried on the extremity of the valve rod 22, the latter, as more clearly shown in Figure 3, carrying the valve proper 24, 100 which is adapted to close against the seat 25. An auxiliary flush pipe 26 leads from the float valve 20 directly into the flush tank 14; it being noted in this regard that the float valve is accordingly adapted to operate independently of the main flush valve of the tank. The float valve is so arranged that should the water within the basin 12 for any cause fall below the level at which it should be maintained for a proper liquid 110 seal, the valve will open, allowing a quantity of water to flow from the flush tank

into the auxiliary compartment and from thence into the bowl proper, whereupon the liquid seal will again be established and maintained at its proper depth or height.

- 5 From the foregoing it will be observed that should the flushing of a closet bowl emptying into the same soil pipe as my improved bowl set up a vacuum and thus cause a siphoning of the liquid seal, the
- 10 float valve will immediately operate and discharge water into the bowl so as to re-establish the liquid seal thereof. Further, should the bowl be left for a considerable time without flushing there will be no
- 15 danger of escapement of sewer gases ordinarily caused by the evaporation of the water of the liquid seal, as with my improved bowl any evaporation of the water of the liquid seal will be immediately compensated for by a new quantity of water
- 20 being discharged into the auxiliary compartment and then into the bowl proper. For the same reason, any spilling of the water of the liquid seal, such as may be
- 25 caused by wind pressure down the vent pipe, will be immediately compensated for and the liquid seal reestablished. The auxiliary compartment will at all times be maintained in a clean and sanitary condition, as
- 30 each time the bowl is flushed the level of the liquid seal will be lowered, causing a corresponding flushing of the auxiliary compartment.

Having thus described and explained my invention, I claim and desire to secure by Letters Patent:

A closet bowl comprising a body portion having a downwardly extending trap wall, an auxiliary compartment protruding from the body portion of the bowl and formed integrally therewith, said auxiliary compartment being substantially vertical and adapted to house an automatic float valve therein, an air vent communicating with the body portion of the bowl and said auxiliary compartment above the highest level of liquid within the bowl, a liquid outlet communicating with the auxiliary compartment and with said bowl below the level of the bottom of said trap wall, a water inlet supply communicating with the auxiliary compartment, and an automatic float shut-off valve located within said auxiliary compartment, controlling said water inlet and adapted to automatically maintain liquid at a predetermined height in the liquid seal of the bowl.

Signed at New York, borough of Manhattan, in the county of New York and State of New York, this 10th day of August, A. D. 1921.

JACOB H. BODINGER.
